UNITED STATES PATENT OFFICE

2,063,970

ENGINE

Robert D. Young, San Francisco, Calif.

Application January 10, 1930, Serial No. 419,926

9 Claims. (Cl. 123—50)

My invention relates to improvements in simple cycle engines, and it consists in the combinations, constructions and arrangements herein-after described and claimed.

5 An object of my invention is to provide a simple cycle engine which makes use of but few parts. For each cylinder I provide a compound piston which is connected to a crank shaft by a connecting rod. I also provide what I term an anchor or fixed piston which cooperates with the compound piston in a manner hereinafter described.

The use of the compound piston makes it possible to cover the firing mechanism whether it 15 be a spark plug or an oil injector, and to keep this mechanism covered until the instant of firing, whereupon the mechanism will be automatically uncovered for firing. All poppet valves, rocker arms, push rods, cams and gears, etc., are 20 done away with, with the exception of a single valve for controlling the intake port to the cylinder. This intake valve may be a standard automatic check valve or a cam or eccentric actuated valve if desired.

25 Other objects and advantages will appear as the specification proceeds, and the new and novel features of the device will be particularly pointed out in the claims hereto annexed.

My invention is illustrated in the accompanying drawing, in which:

30 Figure 1 is a vertical section through the device,

Figure 2 is a vertical section at right angles to that shown in Figure 1,

35 Figure 3 is a sectional view showing the compound piston in its lowermost position, and further shows fuel injectors used in place of the spark plugs, and

Figure 4 shows a modified form.

40 In carrying out my invention, I provide a cylinder 1 that may be air-cooled by means of fins 2, water-cooled, or cooled by other means if desired. The cylinder is mounted upon a crank case 3 of any desired shape. As many cylinders as desired 45 may be carried by the crank case and either arranged longitudinally with respect to a crank shaft 4 or radially about the crank shaft, the cylinders being of odd or even number. With an even number of cylinders, the engine will be better balanced than with an odd number of cylinders. The cylinder 1 has a removable head 1a bolted or otherwise secured thereto.

45 Within the cylinder 1 mount what I choose to call a compound piston 5. This piston is slidably received within the cylinder and is connect-

ed to the crank shaft 4 by means of a connecting rod 6. The compound piston has a removable head 5a. A locking ring 5b may be compressed by inserting projections through openings 5c and this permits the removal of the 5 head 5a.

Within the compound piston I mount an adjustable firing head or piston 7, and this piston is pivotally secured to the cylinder 1 by means of trunnions 8. The best results are obtainable 10 by pivoting the adjustable piston 7 so that it can swing and automatically align itself with the longitudinal axis of the compound piston during the movement of the latter.

The adjustable piston 7 has slots 9 therein for 15 slidably receiving the wrist pin 10 connecting the compound piston with the rod 6. The compound piston 5 has slots 11 for receiving the trunnions or pin 8 during the movement of the compound piston.

20 I will now set forth the various ports used in the engine. These ports are smaller in area than those usually provided, because gases under pressure are moved through the engine in a new and novel manner to be hereinafter described, and I 25 have found that since these gases are under pressure, they can be forced through smaller ports.

20 In Figure 2 it will be seen that the cylinder 1 has an intake port 12, this port being controlled 30 by a check valve 13 that permits gas, air, or other fluid to enter the cylinder 1 but not to leave it. A pipe 14 communicates with the valve controlled passageway, and this pipe may be connected to a carburetor or to an air compressor if desired. 35 The valve 13 may be positively actuated, and to accomplish this it is merely necessary to operatively connect the valve to the crank shaft 4 so as to have it timed by the turning of the crank shaft without noisy gears.

40 The cylinder 1 also has a passageway or bypass 15 that is designed to communicate with inlet ports 16 in the compound piston 5 when the compound piston is at the top of its stroke as shown in Figure 2. As many passageways or 45 by-passes 15 and as many intake ports 12 may be provided in the cylinder 1 as desired. In like manner, as many intake ports 16 in the compound piston 5 may be provided as desired.

The compound piston 5 also has exhaust ports 50 17 that are preferably disposed ninety degrees around the compound piston from the intake ports 16. The ports 17 register with exhaust pipes 18 (see Figure 1) when the compound piston 5 is at the top of its stroke. It should be 55

noted at this point that Figure 2 shows the exhaust pipes 18 as being the same shape, oval in cross section, as the ports. This shape permits the pipe to cut through the air should the engine 5 be used in airplanes, and to thus reduce the wind resistance and drag caused by the pipes.

It should further be noted from Figure 2 that spark plugs 19 are carried by the cylinder 1 and are normally protected by the wall of the compound piston 5. However, when the compound piston is at the bottom of its stroke, the inlet ports 16 register with the inner ends of the spark plugs 19. The passing of a current between the terminals of the spark plugs will fire the gas 10 within the compound piston 5. I will shortly describe how the gas gains entrance to the inside of the compound piston.

I do not wish to be confined to spark plugs as being the only means for igniting the gases. Air 20 may be compressed within the compound piston 5, and the inlet ports 16 may uncover fuel injectors 20 as shown in Figure 3. These fuel injectors will force the required amount of fuel into the compound piston, and the burning of 25 the fuel will instantly take place in the same manner as in oil burning engines. It should be noted that the fuel injectors will be protected by the compound piston 5 in the same manner as the spark plugs 19 are protected. This prevents 30 the rapid carbonizing of the oil on the outlet ends of the injectors, and the injectors will therefore function for a longer period of time than is now possible where they are subjected continuously to heat of the gases. The spark plugs 35 or fuel injectors are briefly exposed upon the stopping of the compound piston on its down stroke. This protects the devices from the heat of the explosion except for the instant of firing.

From the foregoing description of the various 40 parts of the device, the simplicity of operation thereof may be readily understood.

As already stated, air, gas, or other fluid, is received in the top of the cylinder 1 through the inlet ports 12. The gas may be sucked in on the 45 downward stroke of the compound piston 5, or it may be forced in under pressure during this same stroke. The piston 5 on its up stroke will automatically close the check valve 13 due to the pressure of the gas or air upon the valve. Further movement of the compound piston 5 in 50 an upward direction will compress the gas or air. This compressing will continue until the compound piston reaches the top of its stroke and causes the inlet port 16 to register with the 55 passageway 15.

At this instant the air or gas under pressure in the top of the cylinder 1 will immediately flow under any desired pressure through the passageway 15 and into the interior of the compound 60 piston 5. The fluid within the compound piston 5 will be at a slightly greater pressure than it was in the cylinder 1 prior to compressing, because the capacity of the interior of the compound piston 5 is slightly less than the capacity 65 of the cylinder 1 when the compound piston 5 is at the bottom of its stroke, which is a great advantage for an oil engine.

Before the fluid has had a chance to reach the exhaust port 17, the piston 5 will start on its 70 downward movement and the ports 17 will be moved out of registration with the exhaust pipes 18. The gas will therefore be trapped and will be recompressed by the downward movement of the piston 5. The adjustable piston 7 now co- 75 operates with the compound piston 5 to compress

the gas within the piston 5. When the compound piston 5 reaches the bottom of its stroke, the ports 16 will uncover the spark plugs 19 or the fuel injector 20, and an explosion or a burning of the gas within the compound piston 5 will 80 immediately take place.

It should be kept in mind that during the downward movement of the compound piston 5 in compressing the gas within the compound piston, a new charge of gas or air is being drawn 10 into the top of the cylinder 1.

The firing or burning of the fluid within the piston 5 will instantly cause it to move upwardly and to compress the air or gas in the top of the cylinder 1. The upward movement of the compound piston 5 is the power stroke of the engine. When the compound piston again reaches the top of its stroke, the inlet port 16 registers with the passage 15 and the compressed charge of air or gas passes from the top of the cylinder 20 into the piston 5. The new fluid rushing under pressure into the compound piston forces the burnt fluid out through the exhaust ports which are registering with the exhaust ports and pipes 18. The timing of the engine is such that the piston 5 starts on its down stroke when it is completely filled with new gas and after the exhaust gas has been discharged. The simple cycle is now repeated.

It will be seen from the above that the engine 30 fires for every up stroke of the compound piston 5. It will further be seen that the spark plugs or fuel injectors are protected by the compound piston until the very time of use of these mechanisms.

The gases are exhausted at the center of the cylinder 1 rather than at the top of the cylinder as is now the practice. This will cause a more equal expansion of the metal in the cylinder when heated at its middle rather than have 40 the top of the cylinder expand more than the remainder of the cylinder as is now the case. I have shown the fins 2 as being longer near the middle of the cylinder 1 than at the ends of the cylinder. The purpose of this is to dissipate the 45 heat more rapidly in the center of the cylinder.

The engine may run at a very low speed because the gas or air will be forced into the firing chamber and will be compressed before being sent into the chamber. This compressing will 50 pre-heat the gas, and this will make it possible to run the engine at a slower speed and also makes it possible to make a quick start without warming up the engine.

It should further be noted that the firing stroke 55 takes place while the compound piston is moving upwardly and against the force of gravity. This is possible by the use of the compound piston and the adjustable piston. The moving of the compound piston upwardly on the firing stroke 60 also compresses the gas or air in the top of the cylinder. The moving of the compound piston downwardly compresses the gas or air in the piston 5. It will therefore be seen that a cushioning effect is provided for the piston when moving in 65 either direction. This makes it possible to use a piston having considerably more weight than the piston in the present types of engine.

There is no dead point for lash or slap in the compound piston 5 because, as already stated, it 70 is cushioned on its upward stroke and also cushioned on its downward stroke. A compressing of gas or air takes place during both movements of the compound piston.

The new gas comes in on top of the exhaust 75

gas and forces the exhaust gas out from the compound piston. The pressure of the gases within the cylinder and piston permits smaller ports to be used than are now used on standard engines.

5 The engine differs from the standard two-cycle engine in that it takes in new gas at the top of the cylinder instead of at its bottom. No crank case compression is used. The compound piston 10 5 provides the necessary compression for the gases. The compound piston 5 and the adjustable piston 1 differ from the usual type of piston in the standard two-cycle engine.

It is obvious that the compression chamber in 15 the top of the cylinder can have a certain definite capacity ratio with respect to the explosion chamber within the compound piston 5. In this way, any predetermined pressure may be determined in the cylinder and this pressure changed to a 20 different or the same one in the explosion chamber.

The term fluid is used in the claims to denote air, vapor, gas, or charge.

I wish to further emphasize that the engine 25 may be charged under pressure and is exhausted under pressure. The supercharging feature is built into the engine and forms a part of the simple cycle. The exhaust gases are rapidly removed because they are exhausted under pressure. 30 The compound piston carries the stress of compression, explosion and expansion and the cylinder wall 1 may therefore be lighter than is usually the case because the cylinder merely acts as a 35 guide for the compound piston.

35 The device eliminates the use of a piston rod and piston rod packing in the cylinder proper, and thus utilizes the space normally displaced by the piston rod. The engine is not necessarily to be classed in the hydro-carbon group. It can be 40 used with steam or any other expanding fluid.

The fluid forced into the compound cylinder is 45 preheated from the compressing of it in the cylinder. Also, the fluid may be delivered to the cylinder 1 preheated and under pressure. The cylinder may be formed from heat absorbing metal.

The carbon may be cleaned from the engine 50 by first removing the spark plugs and then aligning the ports of the compound piston 5 with the 55 openings for the spark plugs. A carbon scraping tool may now be inserted through the aligned ports.

In Figure 4 I show the piston 1 adjustably connected to the cylinder 1. Members 50 are rotatably mounted in the cylinder wall 1, and links 51 are connected to the eccentric portions 52 of the members and are pivotally secured to the anchored piston 1 at 53. Arms 54 on the members 50 may be swung for raising or lowering 60 the piston with respect to the cylinder 1. In this way the capacity of the combustion compartment within the compound piston 5 may be varied to bring forth the greatest amount of 65 engine efficiency.

65 Due to the fact that I vary the compression and also the temperature, I can eliminate the injectors by drawing in the fuel with the air through an ordinary jet outside of the cylinder 70 in much the same manner as in using a carburetor.

75 Although I have shown and described two embodiments of my invention, it is to be understood that the same is susceptible of various changes, and I reserve the right to employ such changes

as may come within the scope of the invention as claimed.

Varying the capacity of the combustion chamber will automatically ignite a combustible charge without the use of standard ignition systems or 5 fuel injectors. Variable compression is essential for altitude flying because by this means changes in atmospheric pressure are equalized and a constant compression is maintained whatever the altitude. The present type engines are designed 10 for sea level. High altitude cross country flying is now impossible because present designed motors get tired. My device is capable of variable compression for different altitudes, and the large chamber on top of the compound piston permits 15 the pilot to supercharge the compression chamber.

I claim:

1. In an engine, a cylinder, a compound piston for compressing a fluid in one end of the cylinder, means controlled by the compound piston for 20 passing the compressed fluid from one side of the piston to the opposite side, and an adjustable piston cooperating with the compound piston for again compressing the fluid.

2. In an engine, a cylinder having a closed end, 25 with an intake communicating with the interior, a hollow compound piston slidable in the cylinder and having a non-recessed head for compressing a fluid in the end of the cylinder, a check valve disposed in the intake for preventing any outflow 30 of the fluid, said cylinder and piston having bypasses for conducting the fluid from the cylinder to within the compound piston at the top portion of the stroke of the piston, and a firing head slidably mounted in the compound piston and 35 adjustably connected to the cylinder, the interior of the compound piston and the firing head constituting an explosion chamber, and means for exhausting the burnt fluid from the explosion 40 chamber under pressure.

3. In an engine, a cylinder, a compound piston slidable therein, a firing head disposed within the piston and being pivotally secured to the cylinder and also being adjustable transversely to align with the cylinder and piston axes. 45

4. In an engine, a cylinder having an intake port, a compound piston forming with the cylinder a compression chamber, an adjustable piston mounted within the compound piston and forming a second chamber in which to compress a gas, 50 said cylinder and compound piston having passages placing the two chambers in communication with each other when the compound piston has compressed the gas in the compression chamber, and means for moving the compound 55 piston for again compressing the gas in the second chamber.

5. In combination, a cylinder, a firing head having radially-extending trunnions connecting the head to the cylinder, said head being spaced 60 from the cylinder, a compound piston having a removable head for permitting the firing head to be moved within the piston, said compound piston having inwardly-extending bosses for receiving a wrist pin, said firing head having 65 slots for receiving the bosses and said compound piston having slots for receiving the trunnions.

6. In an engine construction, a cylinder, a piston mounted therein, an adjustable firing head within the piston and connected to the cylinder 70 and cooperating with the piston for providing a compartment, an eccentric connected to the firing head for moving the latter along the cylinder, an operating shank secured to the eccentric and projecting through the wall defining the 75

cylinder, and means for actuating the shank, whereby the capacity of the piston compartment may be varied.

- 5 7. In an engine construction, a cylinder, a piston mounted therein, an adjustable firing head within the piston and connected to the cylinder and cooperating with the piston for providing a compartment, eccentrics connected to the firing head on diametrically opposite sides thereof, operating shanks secured to the eccentrics and projecting through the wall defining the cylinder, and means for actuating the shanks, whereby the capacity of the piston compartment may be varied.
- 10 8. In combination, a cylinder, a firing head having means connecting the head to the cylinder, said head being spaced from the cylinder, a hollow sleeve piston having a removable head for permitting the firing head to be moved within
- 15 20 the piston, said hollow sleeve piston having in-

wardly-extending bosses for receiving a wrist pin, said firing head having slots for receiving the bosses and said hollow sleeve piston having slots for receiving the trunnions.

- 5 9. An engine comprising a cylinder, a firing head anchored in the cylinder and being spaced therefrom, a hollow sleeve piston mounted in the cylinder and slidably receiving the firing head, means for feeding a combustible mixture into the space between the hollow sleeve piston 10 and the firing head, and means for adjusting the firing head during the operation of the engine so as to vary the capacity of the space within the hollow sleeve piston when the piston is at its extreme compression stroke position, whereby the 15 pressure within the hollow sleeve piston can be raised to a point for automatic or controlled ignition.

ROBERT D. YOUNG.
